UNITED STATES PATENT OFFICE.

EDWARD HENRY FRIEND, OF KATOONBA, NEW SOUTH WALES, AND ALBERT GILEAD BENTLEY, OF MELBOURNE, VICTORIA, AUSTRALIA, ASSIGNEES TO THE FRIEND BENTLEY ELEMENTS COMPANY LIMITED, OF MELBOURNE, AUSTRALIA.

INTERNAL-COMBUSTION ENGINE.

Application filed April 12, 1924. Serial No. 706,202.

To all whom it may concern:

Be it known that we, EDWARD HENRY FRIEND and ALBERT GILEAD BENTLEY, both subjects of the King of Great Britain, residing, respectively, at Katoomba, New South Wales, Australia, and Reddam House, 409 Lonsdale Street, Melbourne, Victoria, Australia, have invented certain new and useful Improvements in or Relating to Internal-Combustion Engines, of which the following is a specification.

This invention relates to internal combustion engines of the type in which the working piston operates in conjunction with an abutment of fixed piston type extending into a sleeve on the working piston.

One object of the invention is to provide a simplified and more efficient construction of engine in which the working stroke exerts a pulling action on the connecting rod so as to eliminate bending stresses. Another object is to improve the cooling of the abutment and the working piston. A further object is to facilitate the fitting of the abutment, piston and connecting rod and the assembling of the parts. A still further object is to improve the supply of the charge and the exhaust of the products of combustion.

The accompanying drawings illustrate one embodiment of the invention:—

Figures 1 and 2 are, respectively, a vertical section and an inverted sectional plan of the said embodiment.

A is the engine cylinder. B the moving piston with sleeve *b* upon or into the upper end of which the flange of the piston is screwed. C' is the fixed abutment or stationary piston carried by the limbs or supports *c* bolted at *c*¹ to the cylinder through spacing members C² near the lower end. D is the connecting rod.

The piston or piston head B is screwed into the outer end of the piston sleeve *b* through the flange *b*¹ provided with piston rings *b*². At the lower end of the piston sleeve are the exhaust ports *b*³ adapted at the end of the outer piston stroke to register with the exhaust channel *a*¹ of the cylinder. For lubrication a lubricating oil pipe G is shown as fitted at the top of the cylinder so that the oil can drop upon the outer face of the piston.

A pump compression space H is provided between the piston head and the top of the cylinder and air or explosive mixture is drawn into this space through the channel *h*¹, which extends downwardly along the side of the cylinder. The piston B on its working stroke compresses the charge above it in the pump space H and as the outer area of the piston is greater than the area of the abutment C' the external volume swept out by the piston is greater than the volume swept out in the working space in the interior of the piston, so that the charge compressed in the pump space H is more than sufficient to fill the working space at the end of the working stroke when the products of combustion escape through the exhaust ports *b*³ and the compressed charge from the pump space H enters through the ports *b*⁴, driving the products of combustion in front of it. The gudgeon pin *d*, to which the upper end of the connecting rod *d* is attached, is carried by a pair of bearing brackets *b*⁵ integral with the piston extensions *b*⁶ which project downwardly on each side between the limbs *c* of the abutment. Between the limbs (the outer faces of which are concentric with the cylinder) and the cylinder wall an annular space is left within which slides the piston sleeve *b*. The gudgeon pin *d* extends diametrically between the two limbs *c*.

The inlet channel *h*¹ leads from a carburettor and supplies the explosive mixture to the pump space H in the head of the cylinder. The cylinder inlet ports *a*² are placed immediately above the abutment C' at one side and the exhaust *a*¹ is at the opposite side, the piston being provided with inlet and exhaust ports *b*³, *b*⁴ at the opposite sides of the sleeve. The charge is admitted to the working space through the inlet channel *h*² leading from the pump space H along the side of the cylinder and the abutment is provided with a deflector *c*³ to direct the inflowing gases upwardly to drive the products of combustion out through the exhaust ports.

The abutment C' is shown with a water cooling space *c*⁴ and the cooling water is admitted and discharged through the channels *c*⁵ in the limbs *c*.

What we claim and desire to secure by Letters Patent of the United States is:—

1. In an internal combustion engine, a cylinder, a sleeved reciprocating piston in the said cylinder, a hollow abutment of fixed piston type extending into the piston sleeve, limbs carrying the said abutment and extending towards the lower end of the cylinder, which limbs are provided with water channels for supply of cooling water to the hollow abutment, spacing members between the said limbs at their lower end and the cylinder and means for bolting the said cylinder, whereby the limbs provide a clear space between them and the inner surface of the cylinder for the passage of the piston sleeve.

2. In an internal combustion engine, a cylinder, a sleeved reciprocating piston in

the said cylinder, an abutment of fixed piston type extending into the piston sleeve, limbs carrying the said abutment, and extending towards the lower end of the cylinder, a space for the piston sleeve being left between the limbs and the cylinder, a connecting rod, a gudgeon pin lying between the abutment limbs and a pair of brackets projecting inwardly from the piston sleeve between the two abutment limbs to carry the said gudgeon pin.

3. In an internal combustion engine as in claim 1, a connecting rod, a gudgeon pin and integral bearing brackets for the gudgeon pin on the piston sleeve, which brackets extend under the fixed water cooled abutment.

EDWARD HENRY FRIEND.
ALBERT GILEAD BENTLEY.
